A. REINHART

FISH BOAT

Filed March 26, 1926

FIG. 2

FIG. 3

FIG. 4

INVENTOR
Adolf Reinhart
BY
Soltan Holashoff
ATTORNEY

UNITED STATES PATENT OFFICE.

ADOLF REINHART, OF HOBOKEN, NEW JERSEY.

FISH BOAT.

Application filed March 26, 1926. Serial No. 97,496.

This invention relates generally to boats, the invention having more particular reference to a novel type of fish boat.

The invention has for an object the provision of a boat shaped to represent a fish.

A further object of the invention is the provision of a fish boat, embodying an adjustable keel, which may be lowered when desired so as to increase the stability of the said fish boat.

For further comprehension of the invention, reference will be had to the following description and to the accompanying drawing, and to the appended claims in which 15 the various novel features of the invention are more particularly set forth.

Fig. 1, of the drawing, is a side elevational view of my improved fish boat, as it would appear when in the water ready for use.

Fig. 2 is an enlarged fragmentary view thereof, showing in particular a rear elevational view of the adjustable keel as used in connection therewith.

Fig. 3 is a similar view, partly in section, 25 showing in particular a front elevational view of the adjustable keel as used in connection with my improved device.

Fig. 4 is an enlarged detail sectional view taken on the line 4—4 of Fig. 3.

As here embodied my improved fish boat comprises a hull 10, of common ordinary construction, such as generally used for boats, and shaped at the bow 11 to represent the head of a fish, and having a stern 12, shaped to represent the tail of a fish, and provided with an upper fin 13 projecting therefrom, and a lower fin 14, hinged to the said stern 12, as at 15, and provided with a suitable tiller post 16 attached thereto, and having a flexible member 17, cord, cable or the like, attached to both extremities of the cross member 18, and extended within the cockpit 19, the latter mentioned being such as will permit my improved fish boat to be steered in the usual well known manner.

The cockpit 19, is provided with seats 20, suitably arranged therein, so as to accommodate passengers. My improved fish boat is also provided with a motor 21, preferably of the gasoline marine type, such as generally used to propel boats, and is operatively connected to the propeller wheel 22, by the propeller shaft 23. The fuel tank 24, is preferably located in the bow 11 of the said hull 10, and is provided with the usual filler cap and is connected to the said motor

21, by a suitable gasoline pipe, the two latter named elements being of common ordinary construction, and not shown in the accompanying drawing.

It will be clearly understood that I do not necessarily confine my improved fish boat to self-propelled boats, but also to boats propelled manually by oars.

Referring in particular to the adjustable keel 25, as used in connection with my improved fish boat, which comprises a flat element having its upper edge 26 suitably shaped to conform to the bottom center line of the said hull 10, and pointed at the front, as at 27, the said adjustable keel 25, being hinged, at the rear, as at 28, to the bottom of the said hull 10, preferably by ears 29 extending downward from the hull 10, and provided with a suitable hinge pin 30, the above mentioned construction being such as will permit the adjustable keel 25 to be hinged downward, as designated by the dot and dash lines 31.

As a means of operating or hinging the said adjustable keel 25, I have provided a sector 32, rigidly attached to the said adjustable keel 25, at or near its pointed front 27, as at 33, by bolts, screws, or the like, and extending upward therefrom. The said sector 32 is provided with teeth 34, meshing with a suitable pinion 35, rigidly attached to a cross shaft 36, at or near its center, the said cross shaft 36 being rotatively mounted in suitable bearings 37, conveniently located in the partition 38, which is provided with a top element 39 and ends 40, depressed or formed in the said hull 10, to accommodate the cross shaft 36, and the sector 32. The partitions 38 are also provided with suitable stuffing boxes 41, of common ordinary construction, to prevent the water from leaking into my improved fish boat around the cross shaft 36. The lever 42, is rigidly attached, at its lower extremity, as at 43, at or near one extremity of the cross shaft 36, and is provided with an upper extremity 44, suitably formed as a handle.

As a means of holding the adjustable keel 25 in an upper position, I have provided a spring holder 45, preferably of spring steel, conveniently attached at its center, as at 46, to the said hull 10, and having its extremities 47, curved or suitably bent outward so as to engage the said lever 42, for the purpose as above set forth, it being understood that when the said adjustable keel 25, is

lowered, as designated by the reference numeral 31, that the said lever 42, will engage a second spring holder 46, suitably located, as clearly shown in Fig. 1 of the accompanying drawing.

It will be further understood that my improved fish boat may be suitably painted so as to further represent a fish, also that oars as shown at 50, may be substituted in place of motor 21.

It is obvious that I have provided a fish boat, adapted to be used at amusement parks, and the like, embodying an adjustable keel which may be readily lowered in comparatively deep water, so as to stabilize the said fish boat, so as to prevent accidents from capsizing.

While I have above described the preferred form, construction, and arrangement 20 of the several elements employed, it will be understood that the device is, nevertheless, susceptible of considerable modification therein, and I therefore reserve the privilege of resorting to all such changes as may be 25 fairly embodied within the spirit and scope of the invention as claimed.

Having thus described my invention, what I claim as new and desire to protect by Letters Patent of the United States is as follows:

1. A fish boat comprising a hull shaped at the bow to represent the head of a fish, and having a stern shaped to represent the tail of a fish, and provided with an upper fin 35 projecting therefrom, and a lower fin hinged to the said stern, and provided with a tiller post attached thereto, and having a flexible member attached to a cross member of the said tiller post, as a means of steering the 40 said fish boat.

2. A fish boat comprising a hull shaped at the bow to represent the head of a fish, and having a stern shaped to represent the tail of a fish, and provided with an upper fin 45 projecting therefrom, and a lower fin hinged to the said stern and provided with a tiller post attached thereto, and having a flexible member attached to a cross member of the said tiller post, as a means of steering the 50 said fish boat, said fish boat provided with a gasoline motor operatively connected to a propeller wheel, as a means of propelling the said fish boat.

3. A fish boat comprising a hull shaped at the bow to represent the head of a fish, and having a stern shaped to represent the tail of a fish, and provided with an upper fin 55 projecting therefrom, and a lower fin hinged to the said stern, and provided with a tiller 60 post attached thereto, and having a flexible member attached to a cross member of the said tiller post, as a means of steering the said fish boat, said fish boat provided with oars, as a means of manually propelling the 65 said fish boat.

4. A fish boat comprising a hull shaped at the bow to represent the head of a fish, and having a stern shaped to represent the tail of a fish, and provided with an upper fin 70 projecting therefrom, and a lower fin hinged to the said stern, and provided with a tiller post attached thereto, and having a flexible member attached to a cross member of the said tiller post, as a means of steering the said fish boat, said fish boat provided with a 75 self propelling means.

5. A fish boat comprising a hull shaped at the bow to represent the head of a fish, and having a stern shaped to represent the tail of a fish, and provided with an upper fin 80 projecting therefrom; and a lower fin hinged to the said stern, and provided with a tiller post attached thereto, and having a flexible member attached to a cross member of the said tiller post, as a means of steering the 85 said fish boat, said fish boat provided with a gasoline motor operatively connected to a propeller wheel, as a means of propelling the said fish boat, an adjustable keel hinged to the bottom of the said keel, and a means 90 of lowering the said adjustable keel so as to prevent capsizing of the said fish boat.

6. A fish boat comprising a hull shaped at the bow to represent the head of a fish, and having a stern shaped to represent the tail 95 of a fish, and provided with an upper fin projecting therefrom, and a lower fin hinged to the said stern, and provided with a tiller post attached thereto, and having a flexible member attached to a cross member of the 100 said tiller post, as a means of steering the said fish boat, said fish boat provided with oars, as a means of manually propelling the said fish boat, an adjustable keel hinged to the bottom of the said keel, and a means of 105 lowering the said adjustable keel so as to prevent capsizing of the said fish boat.

7. A fish boat comprising a hull shaped at the bow to represent the head of a fish, and having a stern shaped to represent the tail 110 of a fish, and provided with an upper fin projecting therefrom, and a lower fin hinged to the said stern, and provided with a tiller post attached thereto, and having a flexible member attached to a cross member of the 115 said tiller post, as a means of steering the said fish boat, said fish boat provided with a self propelling means, an adjustable keel hinged to the bottom of the said keel, and a means of 120 lowering the said adjustable keel so as to prevent capsizing of the said fish boat.

8. A fish boat comprising a hull shaped at the bow to represent the head of a fish, and having a stern shaped to represent the tail of a fish, and provided with an upper fin 125 projecting therefrom, and a lower fin hinged to the said stern, and provided with a tiller post attached thereto, and having a flexible member attached to a cross member of the said tiller post, as a means of steering the 130

- 5 said fish boat, said fish boat provided with a gasoline motor operatively connected to a propeller wheel, as a means of propelling the said fish boat, an adjustable keel comprising a flat element having its upper edge suitably shaped to conform to the bottom center of the said hull, said adjustable keel pointed at the front, and hinged at the rear to the bottom of the said hull, so as to permit the 10 said adjustable keel to be hinged downward, a sector rigidly attached to the said adjustable keel, at its said pointed end, and extending upward therefrom, said sector provided with teeth meshing with a pinion rigidly attached to a cross shaft, at its center, said cross shaft rotatively mounted in bearings located in a portion provided with top elements and ends, formed in the said hull, to accommodate the said cross shaft and the 15 said pinion, a lever rigidly attached to the said cross shaft, and provided with a handle, spring holders as a means of holding the said lever so as to hold the said adjustable keel in an upper or lowered position.
- 20 9. A fish boat comprising a hull shaped at the bow to represent the head of a fish, and having a stern shaped to represent the tail of a fish, and provided with an upper fin projecting therefrom, and a lower fin hinged to the said stern, and provided with a tiller post attached to a cross member of the said tiller post, as a means of steering the said fish boat, said fish boat provided with oars, as a means of manually propelling the said fish boat, an adjustable keel comprising a flat element having its upper edge suitably shaped to conform to the bottom center of the said hull, said adjustable keel pointed at the front, and hinged at the rear to the bottom of the said hull, so as to permit the said adjustable keel to be hinged downward, a sector rigidly attached to the said adjustable keel, at its said pointed end, and extending 25 upward therefrom, said sector provided with teeth meshing with a pinion rigidly attached to a cross shaft, at its center, said cross shaft rotatively mounted in bearings located in a portion provided with top elements and ends, formed in the said hull, to accommodate the said cross shaft and the said pinion, a lever rigidly attached to the said cross shaft, and provided with a handle, spring holders as a means of holding the said lever so as to hold the said adjustable keel in an upper or lowered position.
- 30 10. A fish boat comprising a hull shaped at the bow to represent the head of a fish, and having a stern shaped to represent the tail of a fish, and provided with an upper fin projecting therefrom, and a lower fin hinged to the said stern, and provided with a tiller post attached to a cross member of the said tiller post, as a means of steering the said fish boat, said fish boat provided with a self propelling means, an adjustable keel comprising a flat element having its upper edge suitably shaped to conform to the bottom center of the said hull, said adjustable 35 keel pointed at the front, and hinged at the rear to the bottom of the said hull, so as to permit the said adjustable keel to be hinged downward, a sector rigidly attached to the said adjustable keel, at its said pointed end, and extending upward therefrom, said sector provided with teeth meshing with a pinion rigidly attached to a cross shaft, at its center, said cross shaft rotatively mounted in bearings located in a portion provided with top elements and ends, formed in the said hull, to accommodate the said cross shaft and the said pinion, a lever rigidly attached to the said cross shaft, and provided with a handle, spring holders as a means of holding the said lever so as to hold the said adjustable keel in an upper or lowered position.
- 40 11. In a fish boat of the class described an adjustable keel comprising a flat element having its upper edge suitably shaped to conform to the bottom center of the said hull, said adjustable keel pointed at the front, and hinged at the rear to the bottom of the said hull, so as to permit the said adjustable keel to be hinged downward, a sector rigidly attached to the said adjustable keel, at its said pointed end, and extending upward therefrom, said sector provided with teeth meshing with a pinion rigidly attached to a cross shaft, at its center, said cross shaft rotatively 45 mounted in bearings located in a portion provided with top elements and ends, formed in the said hull, to accommodate the said cross shaft and the said pinion, a lever rigidly attached to the said cross shaft, and provided with a handle, spring holders as a means of holding the said lever so as to hold the said adjustable keel in an upper or lowered position.
- 50 12. In testimony whereof I have affixed my 55 signature.
- 55 ADOLF REINHART.
